UNITED STATES PATENT OFFICE.

ERASTUS A. DERRICK AND HENRY F. MEYERS, OF LITTLE ROCK, ARKANSAS.

PAINT-SPRAY.

1,232,510.

Specification of Letters Patent. Patented July 10, 1917.

Application filed November 2, 1915. Serial No. 59,206.

To all whom it may concern:

Be it known that we, ERASTUS A. DERRICK and HENRY F. MEYERS, citizens of the United States, residing at Little Rock, in the county of Pulaski and State of Arkansas, have invented new and useful Improvements in Paint-Sprays, of which the following is a specification.

Our invention relates to improvements in paint sprays, or devices for applying liquid coating compositions.

Our object is to provide a machine of this character which will be thoroughly practical, inexpensive of manufacture by reason 15 of its very simple construction, and which will attain the highest degree of efficiency possible in devices designed to do away with the tedious process of applying paint and like substances by means of brushes.

20 The several advantages of our invention will be hereinafter explained and the features of construction described in detail, reference being had to the drawings which form a part of this application.

25 In said drawings, Figure 1 is an elevation of our spray with a detail thereof shown in cross-section, and Fig. 2 is an enlarged sectional view of the compressed air nozzle and coupling which is a feature of our device.

30 Referring more specifically to the drawings in which like reference characters denote like parts in the two views, the numeral 1 represents a container or receptacle for the paint, and 2 a suitable filling means 35 or opening. Upon the top of the tank are disposed the automatic spring controlled outlet air-valve 3 and inlet valve 4, the purposes of which will be later referred to.

Connected with the bottom of the said 40 tank is the paint feed pipe 5 having the check valve 6 for turning on or cutting off the supply of paint. The coupling 7 serves to connect the said feed pipe 5, the outlet pipe 8 and the air duct 9, and to support 45 and house the air-nozzle 10, and to receive the threaded coupling-nut 11. The said pipes 5, 8, and 9, and the air-nozzle 10 are externally threaded, the nut 11 internally and externally threaded, and the coupling 6 50 internally threaded, all as shown clearly in the sectional view, Fig. 2.

Check valve 12 in duct 9 is for the purpose of controlling the admission of air to nozzle 10. We have shown in Fig. 1 a flexible piping 13 provided at its free end with a spray nozzle 15 and adjacent thereto with

cock 14 by which the painter may control the flow through the spray-nozzle.

In perfecting a thoroughly practical paint spray we have found that it is essential to 60 provide an adequate and comparatively air tight closure for the paint tank or receptacle for the purpose of excluding any foreign substance therefrom and to prevent waste and deterioration of the paint due to evaporation and exposure to the atmosphere. At 65 the same time it is necessary to allow for admission of air to the tank as the paint therein is consumed. Consequently we have provided the inlet air-valve 4.

70 The operation of the device is as follows:

Paint having been poured into the tank 1 through the opening 2, the check valve 12 in air duct 9, which duct is connected with a source of supply of compressed air not 75 shown in the drawings, is opened, allowing the air to flow—at a minimum pressure of 125 pounds—through the air nozzle 10 and on through pipes 8 and 13 out through the spray-nozzle 15. Then the check valve 6 in feed pipe 5 is opened which allows the paint to descend through said pipe. The rapid 80 rush of compressed air from nozzle 10 creates a vacuum behind the delivery end of the nozzle, sucking the paint into and 85 through the pipes 8 and 13 to the spray-nozzle from which it issues in a fine evenly divided spray.

When the painter desires for any purpose 90 to shut off the flow of paint to the spray-nozzle he closes the cock 14. Such closure causes the flow of air—until check valve 12 be turned—to pass up through pipe 5 into the paint container. It is therefore necessary 95 to have a suitable outlet for such excess air and to this end we have provided the outlet air-valve 3 above referred to. The passage of compressed air up through the paint in the tank serves to agitate and thoroughly mix the same and thus renders unnecessary any stirring to keep the liquid in the required condition, to mingle readily and evenly with the air as it passes through the pipes and spray-nozzle.

100 The cover 1^a for the tank provides easy access thereto for the purpose of cleaning, and the pipes and parts of the coupling and air-nozzle may be readily disengaged for a like purpose, which is, of course very important in order to remove such paint as adheres to the insides of the tank, pipes, and coupling, before it dries out.

Having described the features and advantages of our invention, what we claim as novel and desire to secure by Letters Patent, is:

- 5 A device of the character described, comprising a substantially air tight and dust proof liquid container, a closure therefor, a feed pipe leading therefrom, a compressed air supply duct, a coupling connecting said
- 10 feed pipe and said duct, an outlet pipe leading from said coupling, a cut-off means in said outlet pipe, and automatic air inlet and air outlet valves for said container communicating with the interior of the container and the outside atmosphere, said out-
- 15

let valve coöperating with said cut-off means and compressed air supply duct to provide for agitation of the mixture within the container by said compressed air, and said inlet valve serving to supply the necessary air to 20 the interior of said container to prevent the formation of a vacuum therein and consequent stoppage of the flow of the mixture through said feed pipe.

ERASTUS A. DERRICK.
HENRY F. MEYERS.
